CLAIM

The ornamental design for a cap, as shown and described.

DESCRIPTION

FIG. 1 is a side perspective view of my design for a cap; FIG. 2 is a front elevational view thereof, shown at an enlarged scale;

FIG. 3 is a front perspective view thereof, shown without the insert and at an enlarged scale;

FIG. 4 is a top plan view thereof, shown at an enlarged scale; FIG. 5 is a top plan view of FIG. 3;

FIG. 6 is a top plan view of the insert, shown without the cap for ease of illustration, as shown at an enlarged scale; and, FIG. 7 is a perspective view of FIG. 6.

The broken line showing of a bottle is for illustrative purposes only and forms no part of the claimed design.
